C. M. GENTHNER,
COMBINATION STOVE,
APPLICATION FILED SEPT. 30, 1919.

1,348,709.

Patented Aug. 3, 1920.

UNITED STATES PATENT OFFICE.

CHARLES M. GENTHNER, OF READING, PENNSYLVANIA, ASSIGNOR TO THE READING STOVE WORKS, ORR, PAINTER & CO., OF READING, PENNSYLVANIA, A CORPORATION OF PENNSYLVANIA.

COMBINATION-STOVE.

1,348,709.

Specification of Letters Patent.

Patented Aug. 3, 1920.

Application filed September 30, 1919. Serial No. 327,484.

To all whom it may concern:

Be it known that I, CHARLES M. GENTHNER, a citizen of the United States, residing in Reading, Berks county, Pennsylvania, have invented certain Improvements in Combination-Stoves, of which the following is a specification.

My invention relates to combination coal, and gas or liquid fuel burning stoves, and comprises certain improvements in connection with a burner employed for heating the oven. I have provided a special form of burner which may be employed with ordinary gas, or with a gaseous vapor developed from a suitable liquid fuel, and one object of my invention is to arrange the parts so that when the valve is operated for the passage of the gas, vapor, or other burning medium, the burner will be brought into operative position, and a flame deflecting plate will be raised into proper position for co-operation with the burner in directing the flame and products of combustion to the oven in the most efficient manner. A further object of my invention is to provide means for carrying off the spent products of combustion, and a still further object is to provide a simple and compact structure and one not likely to get out of order.

These and other features of my invention are more fully described hereinafter, reference being had to the accompanying drawings, in which:

Figure 1, is a perspective view of sufficient of a stove to illustrate my improved burner structure in its relation to the oven of such stove.

Fig. 2, is a cross sectional elevation on the line II—II, Fig. 1.

Fig. 3, is a sectional plan view on the line III—III, Fig. 2.

Fig. 4, is an edge view of a flame impinging or deflector plate within the scope of my invention and Fig. 5 is an end view showing the relation of the gas valve to the burner.

The front of the stove is indicated at 1, and the oven chamber is shown at 2. Beneath the front of the oven chamber is an auxiliary chamber 3, in which is located a special form of a burner 4 having a series of perforations throughout its length and having at one end a mixing chamber 11.

The burner is mounted in the present instance on the gas supply pipe 5 at one end and in a bearing in the frame of the stove 55 at the opposite end, but it may be mounted in any suitable manner.

Pivoted to the frame of the stove at 9^a is a deflecting plate 9 which is turned on its pivots on the rotation of the burner 4 which 60 in the present instance has cam lugs 4^a at each end which come in contact with the plate 9 and hold it in the raised position.

On the end of the burner is the ordinary 65 mixing chamber having means for regulating the supply of air to the burner—6 is a gas valve having a handle 5^a, and on the burner is a projection 7 which is shaped as shown in Figs. 1, 3 and 5, and partly 70 encircles the handle 5^a of the gas valve and is so situated that when the handle is turned down it will be forced down, turning the burner and raising the deflecting plate 9.

The front of the stove is preferably provided with an aperture 10 affording access to the chamber 3 to permit ignition of said burner, and has a series of perforations 12 for a secondary supply of air.

The deflecting plate 9 which is pivotally 80 mounted at 9^a in the bottom of the oven, lies flat when the gas burner is not in use; and rests upon a shelf 9^b formed in connection with the bottom plate of the oven.

Preferably the deflecting plate comprises 85 two sections of thin metal, 9^c and 9^d, spaced apart as indicated in Fig. 4; one plate having spacing lugs 13. The plates may be secured together by bolts or screws 14.

The oven plate or grid 15 is preferably 90 provided with a solid portion 15^a which is adjacent the deflecting plate 9 when the latter is in the raised position, as clearly shown in Fig. 2, so as to extend the deflecting surface, and beyond this point the plate 15 is apertured, as at 15^b, so that the products of combustion may rise through the same and circulate in the oven.

At the rear of the burner, (looking from 100 the front), the shelf 9^b of the bottom plate of the oven is perforated at 17 for egress of products of combustion after heating the oven, and through such perforations the spent products of combustion may pass to 105

the soot-collecting chamber 18 below the bottom plate of the oven, and any accumulation may be removed through a small opening 19, normally closed by a door 19^a at the 5 front of the same. The passage of the spent products of combustion through the perforations 17 is in front of the burner flame and without affecting the same.

When the gas valve 6 is closed by turning 10 the handle 5^a the burner is turned on its pivot by the weight of the deflecting plate 9—the plate closes the opening in the bottom of the oven—and may be weighted, so as to readily close and also turn the burner.

15 Fig. 1, it will be noted, shows the lugs 4^a in two positions; the dotted lines show them in substantially the normal position, and the broken lines show them in the position they assume to hold the pivoted deflecting plate 20 in the raised position.

While reference is made to a gas burner, meaning thereby the use of ordinary commercial gas, it will be understood that my improved structure may be used with natural 25 gas, and that any form of structure wherein liquid fuel is turned into a gaseous vapor may be employed in connection with my improved burner and the operating means therefor, and the coöperating parts.

30 I claim:

1. The combination in a stove, of a pivoted burner structure, a valve controlling the flow of gas to the burner, a flame deflecting plate located above the burner and means 35 actuated by the valve for turning the burner and elevating the deflecting plate when gas is admitted to the burner.

2. The combination in a stove, of a pivoted burner structure, a valve controlling the flow of gas to the burner said valve having 40 a handle, a projection on the burner structure located in the path of the handle of the valve, a pivoted deflecting plate located above the burner and means on the 45 burner for elevating the deflecting plate so that when the valve is turned to admit gas to the burner, the burner will be turned on its pivot and will elevate the deflecting plate.

3. The combination, in a stove, of a chamber at the front of the same below the oven; the front plate having air inlets communicating with said chamber, a burner located 50 in said chamber, a valve controlling the supply of a burning medium to said burner, means carried by the burner for engagement by the valve when the latter is turned to open position to rock or turn said burner, a pivoted flame deflector forming the top of said chamber, and means 55 whereby the flame deflector may be turned on its pivots to raise the rear edge for the 60

passage of flame when the burner is turned upon opening the valve.

4. The combination, in a stove having a chamber at the front of the same below the 65 oven, of a front plate having air inlets communicating with said chamber, a burner located in said chamber, a valve controlling the supply of a burning medium to said burner, an operating handle for said valve, 70 a projection carried by the burner for engagement by the valve operating handle when the valve is turned to open position to turn said burner, a pivotally mounted flame deflecting plate forming the top of said 75 chamber, and lugs carried by said burner whereby said flame deflecting plate may be turned on its pivots to raise the rear edge for the passage of flame when the burner is turned upon opening the valve. 80

5. The combination, in a stove having a chamber at the front of the same below the oven, of a burner located in said chamber, a valve controlling the supply of a burning medium to said burner, a projection on the 85 burner located in the path of the valve handle, a pivotally mounted flame deflecting plate forming the top of said chamber, and cams carried by the burner and engaging said flame deflecting plate whereby the latter may be turned on its pivots to raise the rear edge for the passage of flame when the burner is turned. 90

6. The combination in a stove, of a chamber at the front of the same beneath the 95 oven, a flame deflecting plate covering the chamber when gas is not used,—a burner located in the chamber under the plate and a cam on the burner arranged to raise the plate when the burner is turned and a gas 100 supply pipe for the burner having a hand operated valve, said burner having a portion arranged to be engaged by the valve when turned to the open position.

7. The combination, in a stove, of a chamber at the front of the same beneath the oven, a plate pivotally mounted and covering said chamber when not in use; said chamber having a shelf upon which said plate may rest, a burner located in said 110 chamber, a valve, coöperating means between the valve and burner whereby the latter may be turned or rocked when the valve is opened, and means carried by said burner for turning the plate on its pivots when the 115 burner is rocked or turned in its bearing; said shelf upon which the plate rests having apertures for the circulation of heat and products of combustion when the plate is in the raised position. 120

CHARLES M. GENTHNER.
